[57] CLAIM

The ornamental design for a multiple liquid container, as shown.

DESCRIPTION

FIG. 1 is a perspective view of a multiple liquid container showing my new design;

FIG. 2 is a front elevation thereof, the opposite side being a mirror image of the front shown;

FIG. 3 is a top plan view thereof; and

FIG. 4 is a left side elevation thereof, the right side being a mirror image of the left side.

FIG. 1

FIG. 2

FIG. 3

FIG. 4
